United States Patent Office

Des. 188,212
Patented June 14, 1960

188,212

DIFFUSER PANEL OR SIMILAR ARTICLE

Ernest F. Ruppe, Cleveland, Ohio, assignor to John C. Virden Company, Cleveland, Ohio, a corporation of Ohio

Filed Mar. 3, 1959, Ser. No. 54,820

Term of patent 14 years

(Cl. D48—16)

Fig. 1

Fig. 2

Fig. 3

Fig. 4

Fig. 1 is a bottom plan view of a diffuser panel showing my new design;

Fig. 2 is a side elevational view thereof;

Fig. 3 is an enlarged profile view taken on line 3—3 of Fig. 1 showing the relatively flat catenary curved lower surface of the diffuser panel; and

Fig. 4 is an enlarged fragmentary profile view taken on line 4—4 of Fig. 1.

I claim:

The ornamental design for a diffuser panel or similar article, as shown.
